US0D1078634S

(12) **United States Design Patent** (10) Patent No.: **US D1,078,634 S**
(45) Date of Patent: ** Jun. 10, 2025

(54) **CURRENT INVERTER**

- (71) Applicant: **Victron Energy B.V.**, Almere (NL)
(72) Inventor: **Dennis Van der Zaan**, Eindhoven (NL)
(73) Assignee: **Victron Energy B.V.**, Almere (NL)
(**) Term: **15 Years**
(21) Appl. No.: **35/521,375**
(22) Filed: **Mar. 27, 2024**

(80) **Hague Agreement Data**

- Int. Filing Date: **Mar. 27, 2024**
Int. Reg. No.: **DM/237761**
Int. Reg. Date: **Mar. 27, 2024**
Int. Reg. Pub. Date: **Jun. 21, 2024**

(30) **Foreign Application Priority Data**

- Oct. 1, 2023 (EM) 015035882-0001
- (51) **LOC (15) Cl.** **13-02**
(52) **U.S. Cl.**
USPC **D13/110**
